HOSIERY AND METHOD OF MAKING
THE SAMECharles G. Erickson, Milwaukee, Wis., assignor
to Phoenix Hosiery Company, Milwaukee, Wis.,
a corporation of Wisconsin

Application July 9, 1934, Serial No. 734,295

1 Claim. (Cl. 66—184)

This invention relates to hosiery and more particularly to hosiery practically adapted to production on seamless knitting machinery and yet closely simulating in its final form full-fashioned hosiery. The hose, as produced by the present invention is especially designed and adapted for use by men, being in the nature of socks.

In carrying out the invention the top and leg of the hosiery are knitted in the usual manner, that is, by making the top on a topper and a leg on a legger or a seamless knitting machine, usually of the type wherein a rotating cylinder carrying the needles is continuously rotated and the full number of needles, for example 240, are employed. After the knitting of the leg has been completed one half of the needles are thrown out of action and the cylinder is oscillated with the remaining half of the needles operative in order to knit the heel. Thereafter, a loose course is knitted into the fabric, in order to provide for looping of portions of the heel tabs. After this has been done, the needles which have been utilized to make the heel and the loose course are thrown out of operation, and the other needles, that is, the other 120 needles in the example mentioned, are brought into action to knit the top of the foot of the hosiery. When the knitting of the top has been completed, the same needles that have been in action are utilized to knit the toe portion, although different threads may be supplied for this purpose and the action is varied in that as the knitting of the toe portion progresses one needle at the end of each half swing of the cylinder is thrown out of action at the completion of each course until a half of the toe has been knit, whereupon the action is reversed and one needle is thrown in at the end of each half swing until the full number of needles (120 in the example being used) are again operated. When this has been done the toe portion has been knit. The next step which proceeds immediately upon the completion of the toe portion is the knitting of the sole and for this purpose the same needles are employed al-

though in each oscillation a full half of the needles function so that the courses are of uniform width. Upon completion of the knitting of the sole a loose course is knit into the fabric to adapt it for looping to the heel tabs and a few complete courses are then knit which results in the blank or hose coming from the machine with corners of the sole knit to the heel. After the knitting has been completed the corners of the sole are separated from the heel tabs by simply cutting them therefrom and the

heel tabs may be trimmed off or rounded. The heel tabs in the back of the stocking are then cut along the line in which the seam in the full-fashioned stocking usually occurs. The side edges of the sole are then seamed to the side edges of the top part of the stocking and the ends of the sole are looped to the ends of the heel tabs. The bottoms of the heel tabs are looped together and the edges at the back of the leg of the stocking are seamed to each other. The effect is that of full-fashioned stocking and yet knitting is accomplished on a seamless knitting machine with consequent economy and convenience in production.

Other objects and advantages reside in certain novel features of the construction, arrangement and combination of parts which will be herein-after more fully described and particularly pointed out in the appended claim, reference being had to the accompanying drawings forming a part of this specification, and in which:

Figure 1 is a view in elevation showing the stocking as it comes from the knitting machine but folded in order to illustrate the structure;

Figure 2 is a similar view illustrating how the blank is severed after knitting to adapt it to the subsequent looping and seaming operations;

Figure 3 is a fragmentary view in elevation illustrating how portions of the blank are brought together for looping and seaming operations;

Figure 4 is a view similar to Figure 1 but showing the blank somewhat differently folded for the purposes of illustration;

Figure 5 is a view in elevation of the completed stocking or sock;

Figure 6 is a view in elevation of the blank after the seam has been cut and showing it spread out; and

Figures 7, 8, and 9 are views in cross section taken on line 7—7 of Figure 4 and showing the blank first as it comes from the machine, second as cut, and third as seamed.

Referring to the drawings, the numeral 1 designates the top of the stocking which is knit in the usual way. After the top is knit it is transferred to a legger and the leg 2 is also knit in the conventional fashion. Upon the completion of the leg the heel portion 3 made up of heel tabs 3^a and 3^b is knit, this being accomplished by oscillating the cylinder of the machine and utilizing only half of the needles. Upon completion of the knitting of the heel a loose course is knit in order to provide for a subsequent looping operation which will be hereinafter described.

After this has been done the needles employed for knitting the heel are thrown out of action but still retain, however, the loops of the last course. The other half of the needles is then 5 brought into operation to knit the top part of the foot designated at 5, the cylinder being oscillated for this purpose and courses of uniform width being knit. This action is continued until the 10 knitting of the top part of the foot has been finished. The next operation is the knitting of the toe designated at 6 and made up of portions 6^a and 6^b. The portion 6^a is knit by oscillating the cylinder and utilizing the same needles that had 15 been employed for knitting the top part 5. However, thread of different texture is supplied to the needles which knit the toe and the operation is varied in that at the completion of each oscillation one needle is dropped out of action to 20 secure the narrowing or bulging effect. When the knitting of the toe has progressed to the point of the toe the operation is reversed in that instead of dropping a needle at the end of each course, a needle is added, thus widening instead of narrowing the portion 6^b. The next step 25 consists in knitting the sole 7, which operation is also effected by utilizing the same needles and oscillating the needle cylinder. When the sole 7 has been knit a loose course is added also to provide for subsequent looping operation to be 30 hereinafter described, and a few full courses are added by round and round knitting which results in the formation of the connection portion 8 illustrated in Figures 1 and 4. This completes the knitting of the blank.

35 The portion 8 is then severed and the resulting edges are raveled down after the loose courses adjacent thereto have been transferred to the looper. Prior to this, however, the heel tabs are 40 separated by cutting them apart and the back of the stocking is also cut along the line in which the seam in full-fashioned hosiery usually occurs. Thereupon the edges 11 and 12 of the top part of the foot and the sole are seamed together, as indicated at S. The corners 13 of the heel tabs

are rounded off as at 14 and the rounded off edges 14 are looped together as at L. The edges 15 of the heel tabs are then looped as at L' to the edges 16 of the sole and the edges of the back of the leg are seamed together. This produces what appears to be a full-fashioned sock, illustrated to advantage in Figure 5, and yet is produced on a seamless knitting machine.

While I have shown and described one construction of hosiery and one method of making the same, it is to be understood that the construction shown and the method disclosed have been selected merely for the purposes of illustration or example and that various changes may be resorted to as will be understood by those skilled in the art without departing from the spirit of the invention or the scope of the subjoined claim.

The invention claimed is:

The herein-described method of making hosiery, 20 simulating full-fashioned hosiery, which comprises knitting the top and leg of the hosiery in the usual way on a circular knitting machine, then utilizing a portion of the needles of the machine and an oscillating movement of the cylinder thereof to knit the heel tabs and to incorporate a loose course along an edge thereof, then utilizing the remaining needles and also an oscillating motion of the cylinder to knit in succession 25 the top part of the foot, the toe portion, the sole 30 and to incorporate a loose course in the sole at the rearward edge thereof, utilizing round and round knitting to unite the loose courses by complete courses, severing the complete courses, the heel tabs and also the back of the leg, rounding 35 off the heel tabs, interlooping the loose course of the sole with edges of the heel tabs, interlooping portions of the loose course of the heel tabs together, seaming edges of the sole to edges of the top part of the foot, and seaming the rounded off portions of the edges of the heel tabs together and also seaming the edges of the back of the leg together.

CHARLES G. ERICKSON.
